COMBINATION ICE CUBER AND BEVERAGE COOLER

Charles F. Belshaw, Greenville, Mich.

Application November 7, 1934, Serial No. 751,816

4 Claims. (Cl. 62—112)

The object of my invention is to produce a device by means of which cubes of water ice may be conveniently formed in blocks of ice commonly found in iced refrigerators, in condition to be readily harvested therefrom. A further object of my invention is to provide in connection with the cube-defining means a separable canteen or container adapted to receive a liquid having a normal temperature exceeding that of the ice whereby there may be a transfer of heat from the contents of the container to the cube-defining elements of the structure, thereby hastening the cube defining operation and at the same time cooling the contents of the container. The structure is of such character that the user, after preparing a cocktail mixture may place the same within the container, associate the container with the cube-forming structure, place the same upon a block of ice, and in due course have a supply of defined cubes which may be harvested from the ice block and at the same time a desirably chilled beverage without dilution in a container of convenient form for transportation or use away from the refrigerator.

The accompanying drawing illustrates my invention.

Fig. 1 is an under plan view of the cube-forming element of my combination, some portions being exaggerated in thickness;

Fig. 2 a transverse section of the structure shown in Fig. 1, associated with the canteen element;

Fig. 3 a perspective view of the canteen element, and

Fig. 4 a plan of a blank from which one of the cube-defining elements of the structure may be readily formed.

In the drawing 10 indicates the main body sheet of my cube-forming element, said sheet at opposite edges and perhaps one end, having its edges turned upwardly and inwardly to form lips 11, 11 overlying the main body of the sheet. Secured to the under face of sheet 10 are several coordinated series of cube-defining elements each of which is formed of a plate 12 having the form of a Maltese cross, the ears 13 thereof being foldable on the fold lines 14 to position at right angles to the plane of the central portion of the plate with adjacent edges of adjacent ears substantially in contact. One or more of the ears 13, closely adjacent the fold line is perforated as shown at 15. A perforated dimple 16 is formed at the center of the main body of plate 12, and plate 10 is provided with

a plurality of similar mating perforated dimples 17 whereby placement of the elements 12—13 upon plate 10 may be facilitated, rivets 18 passing through the perforations of the dimples and holding the parts together in relative arrangement, as shown. Plates 12 lacking two or three of the ears 13 may be placed to entirely complete cube definition of the entire series, if desired.

The parts 10 and 12 are preferably formed of a metal having a high heat conductivity and after the parts have been assembled as described, they may be further united by a metal bond, not shown, conveniently formed by dipping in a molten metal bath. The mating dimples 16—17 serve as assembly jigs and assist, with rivets 18, in the desired mechanical metal to metal bonding of the parts 10 and 12 both preliminary to the further metal bonding due to the molten bath treatment and thereafter to prevent rupture of the bonding.

The canteen C may be formed in any desired manner and is provided upon opposite sides and one end if desired, with lips 20 proportioned to be received beneath the lips 11 of the cuber in such manner as to permit intimate contact between the smooth heat-conducting surface 21 of the canteen and the smooth heat-conducting surface 22 of plate 10 or the bonding superposed thereon. The canteen C is provided with a suitable neck 23 closed by a removable closure 24.

Due to the separability of the canteen from the cube-forming structure the canteen is conveniently available as a cocktail shaker, or as a water bottle, which may be easily handled and transported, and the cuber is available for use as a cube-defining element in the absence of the canteen, where speed of cube definition is not essential.

The cuber, being placed upon the surface of a block of water ice, will gradually sink into the block and thus define a multiplicity of ice spuds which may be readily harvested from the block by an ordinary ice pick.

I claim as my invention:

1. An ice cube definer comprising a body plate provided on one face with a plurality of thin metal fins normal to the face of the plate and relatively arranged to form adjacent cells, an independent liquid container having one face separably attachable to the aforesaid main body, the said liquid container and main body being so formed that they may be relatively interlocked.

2. An ice cube definer comprising a main body sheet, and a plurality of unitary cube-defining cells each comprising a series of connected plate-like sections arranged in a closed series each in angular relation to its immediately adjacent fellows and each of said cell units attached to one face of the body sheet with at least two of its corner edges closely adjacent a corner edge of another unit.
- 10 3. An ice cube definer comprising a main body sheet, and a plurality of unitary cube-defining cells each comprising a central sheet section and a plurality of integral sheet sections bent into planes normal to the central section in an-

5 gular relation to immediately adjacent sections to form a closed series, the several central sections being attached to one face of the body sheet with at least two corner edges of its closed series adjacent corner edges of another unit.

5

4. An ice cube definer comprising a main body plate provided with edge lips spaced from and overlying one surface of the plate, and a plurality of heat-conductor fins attached to and depending from the other face of the body plate 10 and relatively arranged to form cube-defining cells.

CHARLES F. BELSHAW.
